(57) **CLAIM**

The ornamental design for a passive diffuser device as shown and described.

DESCRIPTION

FIG. 1 is a front perspective view showing our new design for the passive diffuser device of the present disclosure.

FIG. 2 is a rear perspective view of the passive diffuser device shown in FIG. 1.

FIG. 3 is a rear perspective view of the passive diffuser device shown in FIG. 1.

FIG. 4 is a rear view of the passive diffuser device shown in FIG. 1.

FIG. 5 is a front view of the passive diffuser device shown in FIG. 1.

FIG. 6 is a side view of the passive diffuser device shown in FIG. 1.

FIG. 7 is a side view of the passive diffuser device shown in FIG. 1.

FIG. 8 is a top view of the passive diffuser device shown in FIG. 1.

FIG. 9 is a bottom view of the passive diffuser device shown in FIG. 1.

FIG. 10 is a front perspective view showing our new design for the passive diffuser device of the present disclosure.

FIG. 11 is a rear perspective view of the passive diffuser device shown in FIG. 10.

FIG. 12 is a rear perspective view of the passive diffuser device shown in FIG. 10.

FIG. 13 is a rear view of the passive diffuser device shown in FIG. 10.

FIG. 14 is a front view of the passive diffuser device shown in FIG. 10.

FIG. 15 is a side view of the passive diffuser device shown in FIG. 10.

FIG. 16 is a side view of the passive diffuser device shown in FIG. 10.

FIG. 17 is a bottom view of the passive diffuser device shown in FIG. 10; and,

FIG. 18 is a top view of the passive diffuser device shown in FIG. 10.
